UNITED STATES PATENT OFFICE

ALBERT E. MORELOCK, OF ST. LOUIS, MISSOURI, ASSIGNOR TO DRAFTOGEN COMPANY,
OF ST. LOUIS, MISSOURI, A CORPORATION OF MISSOURI

FURNACE CONSTRUCTION

Application filed November 17, 1930. Serial No. 496,053.

My invention relates to improvements in furnace construction, and has among its objects the production of mechanism adapted to be placed within a furnace, and which shall be simple, sturdy, durable, convenient, economical, reliable, and efficient and satisfactory for use wherever found applicable.

The invention has among its further objects, the production of a mechanism for installation within furnaces, which will increase the efficiency of the furnace, greatly decrease or entirely diminish objectionable smoking of the same, and which will enable the furnace to be suitably operated even with relatively inexperienced help, the furnace so equipped requiring minimum dependence upon the human element for maximum efficiency.

One of the important objects of my invention is the production of furnace construction, in which the combustion of the fuel will be substantially complete, so that practically all of the particles of combustible material and gas within the furnace will be effectively and efficiently burned before passing out through the stack.

Another object of my invention is to form a bridge wall or other walls that may extend along or across the furnace, of metal instead of the more usual refractory material, and to prolong the life of such parts through cooling means, to thereby make such parts last as long as the other parts of the furnace itself.

A further object of my invention is to make these metal bridge wall parts of hollow construction, whereby water or other suitable liquid may flow therethrough to not only cool the same, but whereby the water will be heated so that it may be from thence conducted to any suitable point for use, as for instance to radiators, to the feed water inlet, etc.

A still further object of my invention is to so construct such walls and parts for furnaces, that the same will be made in small sections, which may be arranged in line across the width of the furnace to take up substantially the entire width or space of the same, and if there is any space remaining

between the end sections and the adjacent walls of the furnace, the same may be filled in with refractory material or the like if too small to accommodate an additional section. In this manner, there is no necessity of making special sizes of bridge walls to accommodate different widths of furnaces, the single sized sections being laid end to end to build them up to substantially the desired over-all size, and practically any plumber or steam-fitter may assemble and install such sections without long-training.

As an additional object of my invention, I have provided means for introducing auxiliary air into the heated gases in the furnace, this auxiliary air being introduced in a direction contra to the natural or forced draft thereat, to thereby agitate the heated gases and lengthening their travel so that they will be more completely consumed and burned before being discharged through the smoke stack, these air ports being so arranged that the air discharging therefrom will have been considerably heated prior to its discharge.

Another object of my invention is to provide means for automatically regulating the amount of auxiliary air so admitted into the fire, so that said adjustment will supply such air only when needed.

Many other objects and advantages of the construction herein shown and described, will be obvious to those skilled in the art to which this invention appertains, from the disclosures herein given.

To this end, my invention consists in the novel construction, arrangement and combination of parts herein shown and described and uses mentioned, and more particularly pointed out in the claims.

In the drawings, wherein like reference characters indicate like or corresponding parts throughout the views,

Figure 1 is a longitudinal vertical section taken through one form of furnace;

Figure 2 is a top plan view of the same with the boiler and top of the furnace lifted off;

Figure 3 is a perspective view of one of the wall sections which are laid adjoining

one another across the width of the furnace;

Figure 4 is a cross section of the same taken substantially along the line 4—4 of Figure 3;

Figure 5 is a detail of an outlet piece for giving a spiral twist to the air discharged through the sections;

Figure 6 is a fragmentary section through a different type of furnace; and

Figure 7 is a perspective view of the wall sections used for this type of furnace.

Referring more particularly to the drawings, wherein I have illustrated the preferred embodiments of my invention, 1 indicates a boiler of any suitable size and shape and provided with means for heating or rather conducting the heat from the furnace combustion chamber to the liquid within the boiler, as for example the tubes 2 arranged in banks or series or in any other pattern formation, the heated gases from the combustion chamber entering these spaces between the tubes from adjacent the rear of the boiler, and after having transferred its heat is then discharged upwardly through the smoke stack at the rear of the boiler.

A suitable frame-work or foundation is built up to receive the boiler thereon and to form the combustion chamber, such an enclosure being shown as provided with the brick walls 3 of any desired thickness, and built vertically upwardly to the desired height. Across the front of the furnace is arranged one or more doors or openings 4, to provide access to the interior of the furnace and through which the fuel may be supplied thereto, the fire bed cleaned out, and for various other purposes, the grate being indicated at 5.

The furnace thus shown may have a natural draft, or if so desired, a forced draft may be supplied, as through the blower pipes 6 arranged to enter the furnace adjacent the fire bed, and in the type of furnace shown, preferably from above. An arch wall 7 may be provided across the width of the furnace, intermediate the front and rear ends of the same, whereby the combustion gases will be deflected downwardly thereunder as they travel rearwardly of the furnace.

A second wall 8 may also be provided across the width of the furnace and preferably behind the arch, being sealed against the bottom of the furnace and spaced from the under side of the boiler, so as to further deflect the heated gases upwardly at this point as they travel rearwardly through the furnace, such a wall being generally termed the "bridge" wall, and customarily formed of some sort of refractory material.

Instead of having this wall 8 of refractory material, which burns out rather quickly and thereby causes annoyance and expense in the renewal thereof, I have formed such a wall of metal and keep the same from melting as by providing a waterback or the like,

and whereby such a wall will last practically as long as the furnace itself.

Also, instead of making such a wall of a single piece, I have constructed it in sections, these sections adapted to be laid one adjoining the next one, in a straight line across the width of the furnace, and in the event that the width of the furnace is slightly larger than the overall length of the built-up sections that can be placed therein, the space left between the bridge wall so built up and the adjacent furnace walls may be sealed up with fire-brick, fire-clay or the like. In this manner, it is seen that relatively inexperienced workmen may install such a wall, and the sections are sufficiently small that no part of the furnace need be torn out to permit the entry of these sections thereto for installation. This point is especially important where it is desired to place or re-place a bridge wall in an already set-up boiler.

These sections are made somewhat like the ordinary radiator sections, in that they are of hollow metal construction, and the sections are adapted to abut one against the other to complete the wall formation. These sections 9 may be of the full height of the bridge wall, or if so desired they may be of a lesser height, as shown in Fig. 1, to form "caps" for the bridge wall, the remaining height of the wall being built of a refractory material.

Each of these sections 9 is made of metal, cast or otherwise suitably formed to the desired shape, and in the form shown in the drawings, said sections are of block-like shape, and are formed as a shell with a hollow interior through which the water or other liquid may flow, as will be more clearly hereinafter set forth. Each block may comprise the pair of opposed front and rear wall surfaces 10 and 11, and the pair of opposed end surfaces 12 and 13 joining the front and rear surfaces to complete the peripheral bounding wall surfaces, the top of the block being indicated at 15.

An opening or central chamber 14 is provided through the bottom of the block, this chamber preferably extending upwardly from the open bottom of the block to adjacent said top wall 15, and also extending toward one end, as for example the end 12 of the block but not clear through said end, whereby there is formed a chamber that is closed on four sides and is open only on the bottom and one of the ends of the block.

When the sections are formed in this manner, they may be made all alike, and in order to close that end of the bridge wall closest one or both ends of the bridge, a suitable sealing compound, preferably of refractory material, may be interposed between the wall of the furnace and the bridge blocks. In this manner, the necessity of providing "rights"

and "lefts" is obviated, although, of course, the blocks may be cast in this manner if desired.

In order that the adjoining sections may fit together well, the ends of the same may be provided with narrow ribs 16 thereabout, the ribs of one section preferably wedging against the ribs of the adjacent section, or some other manner of providing a good joint 10 may be had. The adjoined sections may be held in their line formation by positioning a tightening rod through aligned apertures 18 provided thru the sections.

Proper connections may be provided between adjoining sections whereby water may be conducted therethrough, as ports 17, it being noted that this water may circulate through all of the hollow interior of the plurality of sections, from one section to the 20 next, as in the ordinary radiator. This water serves to prevent the sections from burning, and the water that has been heated therein may be from thence conducted to any suitable point, as for example to the feed 25 water intake of the boiler, to heating radiators, etc.

In order to augment the supply of air in the combustion chamber of the furnace and to furnish this additional supply in such form 30 that it will do the most good, I have provided means for pre-heating this auxiliary air before its admission to the combustion chamber, to such a degree that it will be practically as hot as the gases in the combustion chamber 35 itself. To this end, I have provided ducts or openings 19 leading from the central chamber 14 of each block 9, said ducts leading through one of the front or rear walls, as for example the front wall 10 in the type of furnace shown in Figs. 1 and 2 and discharging 40 into the combustion chamber.

The air is admitted to said chambers 14 through the inlet ports 20 leading to said chambers from adjacent the rear walls 11 of 45 the blocks, all of said inlet ports preferably being connected to a common source of air supply, as by the conduit 21, said inlet air being from the same source as that supplied to the main draft pipes 6 if desired.

In order to further increase the efficiency 50 of the auxiliary air thus supplied, I have provided means in each of the outlet ports 19 whereby the air will be as widely dispersed as possible while discharging into the combustion chamber, one manner being by the use of short pipes 22 provided with spiral internal ribs or vanes, to thereby impart a spiral twist to the discharged air. The pipes 22 55 may be at angles to one another if so desired, instead of parallel, so as to obtain a better intermingling of the auxiliary air and the heated gases that have been generated through the fire in the combustion chamber.

Obviously, these heated particles of air discharged into the combustion chamber will

have become highly heater before their discharge and aid in the combustion of the unburned amounts of combustible material in the fire box. The pre-heated gases discharged into the combustion chamber are 70 discharged in a direction contra to the direction of the natural or forced draft thereat and cause an agitation thereat, giving the unburned particles a chance to burn before their discharge up the stack. 75

In order to better control the auxiliary air that enters into the combustion chamber, I have provided automatic means, as for example the thermostatically-controlled closure plate 23 arranged within the air chamber 14, 80 as many plates being provided as there are chambers, or any other suitable form of air control through said outlet ports 19 may be provided.

Each of the plates 23 are pivoted or otherwise suitably mounted in its chamber 14, and so balanced that it will normally leave the ports 19 open, as by providing an extension part 24 to one side of the plate to throw it off balance. A suitable piece of material such as a metal that is expansible to the proper degree under the influence of heat may be arranged to engage with and control the movement of the plates, somewhat as shown at 25. The plates 23 will be in the 90 position indicated in full lines when the 95 thermostatic control is unexpanded, and will be thrown to the position shown in dotted lines when the part 25 is heated to the predetermined degree desired. Thus the proper amount of air and the times of admission will 100 be automatically controlled, the air being admitted when most needed and shut off when no longer desirable.

In certain types of boilers there is very 105 little space between the under side of the boiler and the floor of the furnace, as with most residence types of boilers, and the arch and normal bridge walls are dispensed with. With this type of boiler, as illustrated in part 110 in Figs. 6, the boiler is indicated at 26, with its under side at 27, and the floor of the furnace is indicated at 28.

The sections 29 are formed as hereinbefore 115 described, namely of hollow cast metal pieces adapted to be arranged one adjacent the other in line across the width of the furnace. These sections have a water space 30 between the opposed walls, and the auxiliary air is admitted in a chamber in the sections as at 31 120 and discharged through outlet ports 32 in a direction contra to the direction of the draft thereat. In this manner, the same sort of dispersion hereinbefore described will be had, and a proper intermixture of the heated 125 gases and the additional supply of air will occur before the gases are discharged up the stack, the arrows in the drawings indicating the direction of draft.

Having thus described my invention, it is 130

obvious that various immaterial modifications may be made in the same without departing from the spirit of the same; hence I do not wish to be understood as limiting myself to the exact form, construction, arrangement and combination of parts herein shown and described, or uses mentioned, except as limited by the state of the art to which this invention appertains and the claims hereto appended.

What I claim as new and desire to secure by Letters Patent is:

1. In a furnace having a combustion chamber, a wall across said furnace intermediate the front and rear ends of the same and consisting of a series of adjoining hollow metal sections, and means for conducting air through said sections and discharging the same in a direction contra to the draft of the furnace thereat.
2. In a furnace construction, the combination with a grate, of a wall rearwardly thereof and consisting of a series of metal blocks each having double walls forming a hollow interior, means for passing liquid through said interiors, an air chamber within each block and having air ports leading to and from said chamber, and means for controlling the passage of air from said blocks.
3. In a furnace construction having a combustion chamber, a wall behind said chamber and consisting of a series of metal blocks adjoining one another, means for conducting liquid through said blocks, means for passing air through said blocks to pre-heat said air and thence discharge the same into said furnace, and means for automatically controlling the discharge of said heated air from said blocks.
4. In furnace construction having a combustion chamber, hollow bridge blocks arranged across said furnace, an air chamber in each block and having air inlets leading thereto and air discharge outlets leading therefrom into said combustion chamber, means for conducting liquid through said blocks to cool the same, and thermostatically-operated means for adjustably controlling the discharge of air from said chamber through said outlet ports.

ALBERT E. MORELOCK.
